CLAIM

I claim the ornamental design for a device for attachment to a key, as shown and described.

DESCRIPTION

FIG. 1 is a front, top, left end perspective view of a device for attachment to a key embodying my new design;

FIG. 2 is a front elevational view thereof;

FIG. 3 is a top plan view thereof;

FIG. 4 is a bottom plan view thereof;

FIG. 5 is a rear elevational view thereof;

FIG. 6 is a right end view thereof; and,

FIG. 7 is a left end view thereof.
